H. J. HARMS & G. E. SMALL,
MOLDING APPARATUS FOR HOUSES,
APPLICATION FILED JULY 10, 1909.

1,187,908.

Patented June 20, 1916.

UNITED STATES PATENT OFFICE.

HENRY J. HARMS, OF ORANGE, AND GEORGE E. SMALL, OF WEST ORANGE, NEW JERSEY,
ASSIGNORS TO MONOGRAM CONSTRUCTION COMPANY, OF ARIZONA TERRITORY.

MOLDING APPARATUS FOR HOUSES.

1,187,908.

Specification of Letters Patent. Patented June 20, 1916.

Application filed July 10, 1909. Serial No. 506,960.

To all whom it may concern:

Be it known that we, HENRY J. HARMS and GEORGE E. SMALL, of Orange and West Orange, respectively, in the county of Essex, and in the State of New Jersey, have invented a certain new and useful Improvement in Molding Apparatus for Houses, and do hereby declare that the following is a full, clear, and exact description thereof.

10 Our invention relates to an improvement in molds, and especially to the construction of a set of molds adapted to be used in constructing concrete houses. The set of molds which we have designed is adapted particularly to the construction of monolithic houses, that is to say, to houses which are made of a single block of concrete.

20 The object of our invention is to provide a set of molds of the above character, which will have the requisite strength and sustaining power, which may be readily erected and dismantled, and which has manifold conveniences of different kinds, which will be set forth in detail hereinafter in connection 25 with the description of the particular parts thereof.

We have shown our invention in the accompanying drawings, in which—

Figure 1 is a cross-sectional view of a portion 30 of a house made with our apparatus; Fig. 2 is a cross-sectional view in detail of the roof thereof; and Figs. 3 and 4 are respectively sectional and elevational views of two of the molding plates showing the manner 35 of connecting the same together.

In the drawings we have shown an apparatus adapted to be used in the molding of houses by the pouring into the same of a body of concrete. The concrete may be preferably poured into the molds for the house all at one time, the same comprising a set of base plates 1, having wide bottom flanges 2 and narrower upper flanges 3. Each of the plates 1 is strengthened by a vertical and horizontal rib 4. The plates are also provided with side flanges 5, the side flanges 5 and the upper flanges 3 being provided with bolt holes to permit the plates 1 to be secured together by means of bolts 7. The upper flanges of the plates 1 are provided with recesses 8, as shown in Fig. 1, to receive a corresponding rib 9 attached to the lower flange of the next succeeding tier of plates, or to receive a detachable rod 10 arranged 50 to be received in the recess 8 and in the

corresponding recess 11, as shown in Figs. 3 and 4. The arrangement of the recess 8 and the projection 9, or the alternative arrangement of the recesses 8 and 11 and the rod 10 is provided so as to permit the succeeding tiers of plates to be placed exactly in alinement, and also to permit the pivotal removal of the upper tiers of plates as the set of molds is being dismantled.

After the base plates 1 have been placed 35 in position, a next succeeding tier of plates 12 is applied thereto, the plates 12 being constructed in substantially the same manner as the base plates 1, except that the upper and lower flanges thereof are exactly the same in 70 width. The plates 12 are bolted to the base plates 1 and adjacent plates of the same tier, by means of bolts, as described in connection with the base plates 1. Vertical and horizontal ribs are also provided to strengthen 75 these plates, in the manner described in connection with the base plates 1. All of the remaining plates used in the construction of the mold for the house, except those described hereinafter in detail, are constructed 80 exactly like the plates 12, except for variations in size at different points in the house.

In producing ornamental designs upon the exterior of the house, special molds 13 for this purpose are bolted to the interior 85 of the outer molding plates. This method is used where the design comprises a bas relief or extension inwardly from the primary position of the outer molds. If it should be desired, however, to produce an 90 ornamental design by the opposite method, that is to say, extending beyond the normal position of the molding plates, the mold can be set outwardly out of alinement with the normal position of said plates, and then 95 molding plates 14 can be bolted to said latter outer plates to produce what may be called an intaglio design, as shown in Fig. 2.

Instead of using molding plates for molding the exterior of the roof of the house, the roof 18, as shown in Fig. 2, may be first molded in slabs and then placed in position upon the top of the house to take the place of the exterior molding plates at this 105 point.

Inasmuch as the interior plates provide no point of advantage from which the first plates to be removed may be removed, it is desirable to provide some special means to 110

assist in the removal of the first plates. For this purpose we provide in the interior of the house key plates 24. The key plates 24 are constructed with one or more perpendicular flanges 25 and one or more inclined flanges 26. The inclined flanges 26, if desired, may extend to three sides, or even four sides, of the key plates 24. Each key plate 24 is usually operated with a complementary plate 27, which usually has three straight sides 28, and which is provided with one or more reversely inclined flanges 29 to fit against the inclined flanges 26 of the key plates 24.

15 In the case where the key plates are located in the center or in the face of a flat wall upon the interior of the house it is usual to substitute for one of the square plates of the usual type a number of key plates 24, located at right angles to each other, and a complementary plate 27 to fill up the remainder of the opening left by the square plate. Key plates 24 may also be substituted in the angles or at any other desired point upon the interior or exterior of the house.

20 In order to permit the molding of a smooth floor, each floor of the house is preferably provided with one or more risers 29 to allow the escape of air.

25 At any point in the house where it is desired to attach woodwork, tapestry, or carpets, we make provision for inserting wooden blocks 30 by means of thumb screws

30, the thumb screws 31 being removed before the molds attached thereto are removed.

35 In order to properly brace the exterior and interior sets of molds at various points throughout the house the molding plates are provided with perforated bosses 32 to 40 receive bolts 33 passing from one set of molding plates to the other. A bolt 33 is provided at one end with a slot 34 having a pivoted cross-piece 35 supported upon pivots in said slot, of the same width as the 45 thickness of the bolt, and having at its other end a hole to receive a pivot 37 of a cam 38 having attached thereto an operating arm 39.

45 While we have described our invention above in detail, we wish it to be understood 50 that many changes may be made in the details thereof without departing from the spirit thereof.

55 We claim:—

In a device of the character described, a 55 mold adapted to mold plane surfaces, said mold being made of a plurality of plates having flanges, said flanges having a common pivotal means comprising recesses located between said flanges and a removable 60 rod fitting in said recesses.

In testimony that we claim the foregoing we have hereunto set our hands.

HENRY J. HARMS.
GEORGE E. SMALL.
